G. J. ROSSWORM ET AL

SECTIONAL COVER FOR RECEPTACLES

Filed May 27, 1924

FIG. 1.

FIG. 2.

FIG. 3.

FIG. 4.

UNITED STATES PATENT OFFICE.

GEORGE J. ROSSWORM AND LEWIS WATSON, OF CUMBERLAND, MARYLAND.

SECTIONAL COVER FOR RECEPTACLES.

Application filed May 27, 1924. Serial No. 716,176.

To all whom it may concern:

Be it known that we, GEORGE J. ROSSWORM and LEWIS WATSON, citizens of the United States, residing at Cumberland, in the county of Allegany and State of Maryland, have invented certain new and useful Improvements in Sectional Covers for Receptacles, of which the following is a specification.

10 This invention relates to improvements in covers for receptacles and particularly to sectional covers for refuse receptacles, such as garbage cans and the like.

An object of the invention resides in providing a sectional cover for receptacles of the type above mentioned, wherein a pair of cover sections are hingedly connected at opposite sides of the container, and provided with means for normally swinging said 20 cover sections outwardly and downwardly against the outer sides of the receptacles, locking means being provided for cooperation with said cover sections, adapted to hold them in closed position when desired.

25 Another object of the invention resides in providing a sectional cover for receptacles, such as garbage cans and the like, wherein the cover sections are hingedly connected to the upper free edge of said receptacle, and normally operable by spring members carried by the hinges, to swing the cover sections to open position and retain said covers against the outer sides of the receptacle, and locking means adapted for engagement with 30 one of said sections, which particular section is adapted to overlap the free edges of the remaining section, so that when said locking lever is engaged with the predetermined cover section, it will retain all of said 40 cover sections in closed positions, a latching device being provided in connection with the locking lever, for holding the same in cover locking or closing position.

The invention also includes other objects 45 and improvements in the details of construction and arrangement of the parts for carrying out the invention, as particularly pointed out in the following description and claims, directed to the preferred form of the invention, it being understood, however, that various changes in the specific construction and arrangement of these parts may be made, without departing from the scope and spirit of the invention as described and 50 claimed.

In the drawing, forming a part of this application

Figure 1 is a side elevation of the upper portion of the container equipped with a cover constructed according to this invention.

Figure 2 is a partial elevational view of the container shown in Figure 1, with the cover thereon, taken at right angles to the position of the container in Figure 1, and showing the construction of the locking means for the cover.

Figure 3 is a vertical transverse sectional view through the construction illustrated in Figure 1.

Figure 4 is a plan view of the structure shown in Figure 1, with the cover sections in closed position.

A receptacle as indicated at 1 is of the type generally used for trash receptacles and particularly garbage receptacles, and which have a beaded upper open end as indicated at 2. While the receptacle illustrated is of a cylindrical form, it is to be understood that any other desired shape may be provided, in connection with which the invention is adapted to be used.

A pair of cover sections are indicated at 3 and 4 respectively, which are of semi-circular form having cooperating semi-cylindrical flanges 5, formed thereon, adapted to seat within the upper edge of the receptacle 1, while the outer edges of the sections 3 and 4, as indicated at 6, extend over the beaded edge 2 of the receptacle, and limit the interfitting movement of the flanges 5. The adjacent edges of the cover sections 3 and 4, are adapted to overlap as indicated at 7, and for this purpose are provided with extensions 8, at the free edges of each section extending beyond the beaded portion 9 to provide for the proper overlapping relation of the cover section, while the remaining portions are arranged to have the flanges 6 seated on the upper edge of the receptacle 1, as illustrated.

Hinges 10 composed of hinge plates 11 and 12 respectively, hingedly connected together by a hinge pin 13 are formed in the central portion with a recess 14, in which is positioned the coil spring 15, around the hinge pin 13, the free end 16 of said coil spring being adapted for movement in opposite directions, and normally tending to move the hinge plates 11 and 12, in back to

back relation. The plates 11 are connected at their free edges to the receptacle 1, as illustrated in Figure 3, in any suitable and desired manner, with the hinged pin in spaced relation beyond the periphery of the receptacle, while the free edges of the hinge plates 12 are connected at the central portions of the semi-circular edge of the respective cover sections 3 and 4, as clearly illustrated in Figure 4 of the drawings. The normal tendency of the spring 15, to move the hinge plates about the pivot pin 13 normally tends to move said cover sections 3 and 4, to open position with respect to the receptacle and downwardly against the sides of said receptacle.

In order that the cover section may be retained in closed position, the locking means is indicated generally at 17, which includes a pair of brackets 18 mounted on the outer side of the receptacle immediately below the bead 2, and intermediate the mounting of the hinges 10 thereon. A rocking lever 19 is pivotally connected between the brackets 18, as illustrated, and is provided with a curved end portion 20, adapted to engage the cover section 3, in a manner as illustrated in Figure 2, the end of the lever indicated at 21, to the opposite side of the pivot of said lever from the curved end 20 being adapted to extend outwardly in angular relation with respect to the side wall of the receptacle, when the covers are held by said lever in closed position, so that an operation of the lever may be effected by pushing downwardly on the end 21, so as to move the hook 20 out of the path of movement of the cover section, for permitting them to be moved to open position against the sides of the receptacle. In order that the locking lever may be retained in the position shown in Figure 2, for holding said covers in closed position, a resilient member 22 is provided with offset end portions 23, which are pivotally mounted in a pair of spaced brackets 24, secured to the side walls of the receptacle immediately below the brackets 18, the central portion of the member 22 being adapted to engage a notch 25 formed in the lever, so that it will be retained in the position illustrated in Figure 2, for holding the cover in closed position when the member is engaged in the notch as illustrated.

From the above description, it will be seen that the overlapped edge of the cover section 3 will retain the cover section 4 in closed position when the locking lever 19 is engaged with said cover section, as illustrated in Figure 2, and that when it is desired to open the same, the resilient member 22 may be forced downwardly, so as to release the central portion from engagement

with the notch 25 of the lever, which will permit the same to be swung on its pivot to move the curved end 20 outwardly from engagement with the cover section 3, so that the springs 15 are permitted to move said cover sections 3 and 4 outwardly in opposite directions about the hinge pins 13 and the pivot, and downwardly against the sides of the receptacle 1, at which time the contents of the receptacle may be dumped in a convenient manner for more trash or rubbish and the like to be placed in the receptacle, so that it may afterward be covered by the closure of the sections 3 and 4 and the locking means be resecured, as illustrated in Figure 2.

This invention is also capable of a limited adjustment, so that it may be secured to receptacles of varying size within predetermined limits, in a manner which should be clearly obvious from the construction shown in the drawing, the flanges 6 and the extension 8 permitting of this limited adjustment for the various sizes of containers.

What is claimed is:

1. A cover for containers of the class described comprising a pair of semi-circular cover sections adapted for cooperation to close the open end of the container, the adjacent edges of said sections being adapted to extend into overlapping relation, hinges connecting said cover sections to said container, and having means for normally operating said sections to move them into open position, and a locking lever mounted on the container and adapted to engage one of said cover sections for locking said sections in cooperative cover forming relation on said container.

2. A cover for receptacles of the class described comprising a pair of semi-circular sections adapted for cooperation to close the open end of a container, the adjacent edges of said sections being formed to extend in overlapping relation, in cover forming position, hinges secured to said container and said cover sections, having means for normally moving the cover sections into open position, and locking means for holding said cover sections in closed position including a locking lever pivotally connected to said container intermediate the hinged connections, said lever having a curved end adapted for engagement with one of said cover sections, and a latching member adapted for engagement with said locking lever and adapted to hold the same in cover locking relation, for holding said cover sections in closed position.

In testimony whereof we affix our signatures.

GEORGE J. ROSSWORM,
LEWIS WATSON.
